ABSTRACT OF THE DISCLOSURE

A regenerator for use in devices operating at very low temperatures and having a helical wound slotted strip with ribs thereon to form narrow ducts located perpendicular to the plane of the slots in the strip.

The invention relates to a regenerator comprising a housing with one or more filling masses arranged therein under pretension which filling masses are formed by a wound strip of a perforated material.

This known regenerator has the advantage that between the various flow ducts in the regenerator, transverse exchange of medium is possible. A further advantage is that as a result of the perforations the heat conductivity of the strip of material in the direction of flow of the regenerator is reduced.

A drawback of this known construction, however, is that adjacent turns of the filling mass will become to engage one another, as a result of which the heat transmitting surface is reduced. This drawback is more prominent according as the material of the strip is softer.

Regenerators which have to operate in the very low temperature range must have a filling mass which is manufactured from a material which has a comparatively high specific heat at the said low temperatures. The materials which are to be considered for the said purpose are all rather soft. In addition, the said regenerators must have a very high space factor, it being required for the material to be distributed as evenly as possible to ensure a large heat transmitting surface.

The regenerator according to the invention meets all the said requirements and is characterized in that the material from which the strip is manufactured, has a high specific heat at very low temperatures, the strip being provided with ribs extending at right angles to the longitudinal direction of the strip. The ribs ensure that also in the case of a taut winding, the successive turns do not engage one another. As a result of this a particularly evenly distributed filling mass is obtained. In a further preferred embodiment of the regenerator according to the invention, the material of the strip is lead.

According to a further favourable embodiment of the device according to the invention, the strip has a thickness of approximately 100μ (100 microns) and the ribs have a height of at most 50μ , the perforations being formed by slots which are arranged in rows extending in parallel with one another and in the longitudinal direction of the strip, the mutual distance between the rows being approximately 200μ and the width of the slots being in the order of magnitude of 50μ .

The slots enable the medium, which in the regenerator according to the invention flows in narrow ducts between two turns and two ribs, to flow from one duct into the other duct. As a result of the above dimensions a regenerator has been obtained with a very evenly finely distributed filling mass, a large heat-transmitting surface and a high space factor of approximately 80 to 90%.

The present regenerator may be manufactured accord-

2

ing to the invention by first rolling a strip of material by means of a first shaped rolling device so that a number of recesses arranged in parallel rows is formed the bottom of which has a smaller thickness than the strip, the strip then being subjected to an etching treatment by which a layer of material is removed of which the thickness at least corresponds to the thickness of the bottom of the recesses, the strip then being passed through a second shaped rolling device which provides the strip with ribs.

According to the invention, before subjecting the strip of material to the etching treatment it may be provided on one side with a coating layer which is not attacked by the etching agent. This results in a saving of material because in this case a layer of material is etched away only on one side.

A device for performing the said method comprising a first shaped rolling device which is constructed from a number of plates of a harder material and a number of plates of a harder material which are alternately arranged on a shaft, the radius of the softer plates being smaller than the radius of the harder plates by substantially the thickness of the strip, the harder plates being provided with recesses at regular distances and the device comprising an etching bath and a second shaped rolling device for providing ribs in the strip of material.

In this case the harder plates of the first shaped rolling device have a thickness in the order of magnitude of 50μ , and the softer plates have a thickness of approximately 200μ , the plates, after having been arranged on the shaft, being turned-off and provided with axial notches, the assembly being subjected to an etching treatment or an electrolytic treatment so that the difference in diameter between the harder plates and the softer plates is substantially twice the thickness of the strip of material to be processed. As a result of this it is reached, that during the provision of the recesses, the strip of material is readily forced against the base plate. According to the invention, the material for the harder plates is steel and that for the softer plates is copper.

In order that the invention may readily be carried into effect, it will now be described in greater detail, by way of example, with reference to the accompanying drawing, in which:

FIGURES 1a, 1b and 1c diagrammatically show three perpendicular cross-sectional views of a strip of material suitable to be rolled to a regenerator filling mass.

FIGURES 2a and 2b diagrammatically show a plan view and a cross-sectional view respectively of a regenerator filling mass consisting of a coil strip of material as shown in FIGURE 1.

FIGURE 3 diagrammatically shows a shaped rolling device for providing recesses in a strip of material.

FIGURE 4 diagrammatically shows a side elevation of a plate of the shaped rolling device shown in FIGURE 3.

Referring now to FIGURE 1, reference numeral 1 denotes a strip of a material which at very low temperatures still has a comparatively high specific heat, for example, lead. The strip 1 is provided with a number of slots 2, which are arranged in rows. The strip further comprises a number of ribs 3. In a practical embodiment of the strip the thickness is 100μ while the ribs have a height of 40μ . The slots 2 have a width of 50μ , while the distance between the rows of slots is 200μ . After winding the strip on a core 4, a particularly even and finely distributed filling material with a very high space factor is obtained with these dimensions. The coiled strip is diagrammatically shown in FIGURE 2. From this figure it appears that the successive turns are kept spaced by the ribs 3. As a result of this, narrow ducts 5 are created between the turns and each pair of ribs. In this type of regenerator it is of great importance that the medium can

flow from one duct into the other duct. This flow is possible in the filling mass according to the invention as a result of the slots 2. In addition, the slots 2 restrict the thermal conductivity of the strip in the direction of flow. In this manner an extremely readily operating regenerator for operating at very low temperatures is obtained.

As a result of the very small dimensions, the provision of the slots is particularly difficult. This is done by first passing the strip through a shaped rolling device which provides recesses in the strip. The bottoms of the recesses are then removed by etching.

The shaped rolling device for providing the recesses is diagrammatically shown in FIGURE 3. This shaped rolling device comprises a shaft 6 on which a number of plates 7 and 8 are alternately arranged. The plates 7 are manufactured from copper and have a thickness which corresponds to the distance between the rows of slots. The plates 8 are manufactured from steel and have a thickness which corresponds to the width of the slots. The plates 7 and 8, after having been provided on the shaft 6, are turned-off so that they have the same diameter. Slots are then provided at regular distances in the plates 7 and 8 as is shown in FIGURE 4 for one plate 8.

The coiled strip is then dipped in an etching bath. The etching agent will attack the plates 7 of copper more rapidly than the steel plates 8. After some time, the plates 7 have a diameter which is smaller than the diameter of the plate 8 by twice the thickness of the strip 1. In this comparatively simple manner a shaped rolling device is obtained with which recesses of the desired small dimensions can be provided in the strip.

The ribs 3 can be provided on the strip by means of a suitably shaped rolling device.

The invention provides a regenerator which operates readily in the low temperature range, as well as a method

of and a device for manufacturing the said regenerator.

What is claimed is:

1. A regenerator having a medium flow therethrough comprising a housing, a filling mass in said housing constituted of a helically wound strip having spaced slots therein, said wound strip being of a material having a high specific heat at relatively low temperatures, said strip of material being provided with ribs extending at right angles to the longitudinal direction of said strip whereby narrow ducts are formed parallel to the longitudinal axis of said wound strip, said slots and ducts being substantially perpendicular to each other, and the medium flow through said slots being perpendicular to the medium flow through said narrow ducts, said strip having a thickness of approximately 100μ , the ribs having a height of at most 50μ , said slots being arranged in substantially parallel rows and extending in the direction of the longitudinal axis of said strip, the distance between adjacent rows being about 200μ and the width of each of 20 said slots being about 50μ .

2. A regenerator as claimed in claim 1 wherein said helically wound strip is lead.
